CLAIM

USPC **D15/79-91**

We claim the ornamental design for a refrigerator, as shown and described.

CPC F25D 29/00; F25D 11/003; F25D 2700/08;

DESCRIPTION

F25D 11/02; F25D 13/06; F25D 19/006;

FIG. 1 is a front perspective view of a refrigerator showing our new design;

F25D 2201/14; F25D 2323/00261; F25D

FIG. 2 is a front view thereof;

2323/00262; F25D 2323/00272; F25D

FIG. 3 is a rear view thereof;

2400/361; F25D 2500/06; F25D 2700/02;

FIG. 4 is a left-side view thereof;

F25D 2700/12; F25D 29/005; F25D

FIG. 5 is a right-side view thereof;

29/008; F25D 31/002

FIG. 6 is a top view thereof; and,

See application file for complete search history.

FIG. 7 is a bottom view thereof.

(56) **References Cited**

The broken lines in the figures depict portions of the refrigerator and form no part of the claimed design.
